UNITED STATES PATENT OFFICE

2,570,597

FLEXIBLE PANE AND SCREEN SASH

Charles J. Roos, Muskegon, Mich.

Application March 24, 1948, Serial No. 16,816

1 Claim. (Cl. 160—378)

1

This invention relates to a flexible pane or screen sash construction, the primary object of the invention being to provide a sash wherein a flexible pane or screen, preferably of plastic material, may be readily and easily removed or replaced when it becomes necessary to treat the pane or screen.

Another important object of the invention is to provide a flexible pane or screen sash having means whereby the flexible pane or screen may be stretched to draw the pane or screen taut and hold the pane or screen in its taut condition.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawing

Figure 1 is a longitudinal sectional view through a portion of a screen or flexible pane sash, illustrating the stretching frame in its inactive position prior to the stretching operation.

Fig. 2 is a fragmental sectional view through the sash and pane, illustrating a stretching bar as moved to its stretching position.

Fig. 3 is a fragmental sectional view through a screen sash constructed in accordance with the invention, illustrating a screen as being stretched therein.

Referring to the drawing in detail, the sash comprises a pair of rectangular sections 5 and 6, the section 6 having its inner edge rounded as at 7 to eliminate any sharp corners which would tend to damage the flexible pane or screen to be positioned thereon and stretched.

As clearly shown by the drawing, the section 5 is appreciably wider than the section 6, so that a portion thereof extends over and beyond the inner edge of the section 6, the inner edge of the section 5 being formed with a continuous beveled surface 8. The sections 5 and 6 are constructed to clamp the flexible pane as shown by Figs. 1 and 2 of the drawing, therebetween, while in Fig. 3 of the drawing, a screen indicated by the reference character 9 which may also be constructed of plastic material, is held between the sections 5 and 6.

Bolts indicated at 10 extend through the sections 5 and 6 and draw the sections 5 and 6 towards each other in clamping relation with the pane or screen to be supported by the sash.

2

These bolts 10 are arranged in spaced relation with respect to each other, so that sections 5 and 6 will be securely held together throughout the lengths of the side and end members of the sash.

Cooperating with the beveled surfaces 8 of the section 5, is the stretching frame 11, which is rectangular in formation and comprises unconnected bars that are provided with beveled edges that move over the beveled surfaces 8 of the bars of the stretching frame 11 resting directly on the pane which is constructed preferably of plastic material, and indicated in Figs. 1 and 2 of the drawing by the reference character A.

15 The rectangular stretching frame is provided with enlarged openings 12 which openings are so arranged that when the stretching frame is positioned within the section 5, the openings 12 will register with openings 13 formed in the rectangular section 5 to accommodate the securing screws 14.

It might be further stated that the lower edge of the rectangular stretching frame 11 is rounded as at 15, presenting a curved surface for contact 25 with the pane or screen being stretched to insure against the stretching frame damaging the pane or screen to be mounted.

In Fig. 3 of the drawing, I have shown a semi-rigid backing strip 16 on which the screen 9 rests, 30 to brace the screen and prevent damage to the screen during the stretching operation.

From the foregoing it will be obvious that when a flexible pane or screen is to be positioned in the sash, the edges of the pane or screen are disposed between the sections 5 and 6, the bolts 35 10 passing through openings in the pane or screen.

As the strips of the frame 11 are drawn into engagement with the beveled edges of the section 5, it is obvious that the strips of the stretching frame will be moved into close engagement with the pane or screen being stretched, causing the pane or screen to bend as shown by the drawing, causing the pane or screen to become taut.

The openings of the strips of the stretching 45 frame, being appreciably larger than the adjusting screws, the strips may move in a manner as described to accomplish the purpose of the invention.

What is claimed is:

50 A screen embodying a screen frame comprising a pair of outer and inner frame sections secured together, between which wire mesh material is clamped, the inner edge of the outer section of the frame being beveled, said beveled inner edge 55 extending a substantial distance beyond the inner

edge of the inner screen frame section, a stretcher frame embodying independently movable sections having beveled surfaces resting against the beveled inner edge of the outer frame section, said stretcher frame also resting against the wire mesh material beyond the inner edge of the inner screen frame section, and means for moving the sections of the stretcher frame over the beveled surface of the outer section of the screen frame, and against the wire mesh material stretching 10 said wire mesh material within the frame.

CHARLES J. ROOS.
